Donald L. Hopcraft, 5322 S. Angela Road,
Memphis, Tenn.

Filed Dec. 23, 1960, Ser. No. 63,313

Term of patent 14 years

(Cl. D2—3)

Fig. 1.

Fig. 3.

FIGURE 1 is a front perspective view of water heating and dispensing unit for use in making hot beverages, embodying my new design, the back being substantially plain;

FIGURE 2 is a front elevation thereof, with a portion of the front of the base broken away to illustrate the configurational details of the top of the tray element;

FIGURE 3 is a horizontal transverse section view taken along the line 3—3 of FIGURE 2; and

FIGURE 4 is a side elevation thereof, the opposite side being the same.

I claim:

The ornamental design for a water heating and dispensing unit for use in making hot beverages, as shown and described.
